CARBURETOR

Robert F. Bracke, Arlington Heights, Ill., assignor,
by mesne assignments, to R. F. Bracke & Com-
pany, Chicago, Ill., a partnership composed of
Hazel B. Bracke and Robert Anderson

Application October 20, 1950, Serial No. 191,260

4 Claims. (Cl. 261—63)

1

My invention relates to carburetors and is more particularly concerned with, but not necessarily limited to, a compact, simple, inexpensive, and efficient carburetor especially adapted for small tools and similar uses and capable of operating effectively in all positions.

An object of my invention is to provide such a carburetor having a new and improved diaphragm arrangement for controlling the flow of fuel.

A further object of my invention is to provide such a carburetor having a new and improved arrangement of fuel passages.

Another object of my invention is to provide a multi-jet carburetor having new and improved means for preventing back-bleed.

Still another object of my invention is to provide a carburetor having a new and improved air valve.

Another object of my invention is to provide a new and improved carburetor wherein the number of close tolerances is reduced to a minimum and which accordingly can be manufactured inexpensively by mass production methods.

Other objects and advantages will become apparent as the description proceeds.

In the drawings:

Fig. 1 is a sectional elevational view of a preferred embodiment of my invention;

Fig. 2 is an enlarged sectional view of the valve means for preventing back-bleed; and

Fig. 3 is an assembly view largely in vertical section showing a modified form of my invention and its associated fuel tank.

Referring first to the embodiment of Figs. 1 and 2 it will be seen that I have illustrated a carburetor having a main body 10 providing an air inlet 12 communicating with a choke bore 14 containing the usual choke valve 16. A venturi 18 is between the choke bore 14 and throttle bore 20, the latter containing a throttle valve 22.

Fuel is supplied to the carburetor through an inlet 24 communicating with a chamber 26 immediately beneath the main fuel valve 28 which controls communication between the chamber 26 and passages leading to the main fuel jet 30, idle jet 32, and orifice 34. The valve 28 is of frustoconical shape and may be integral with or attached to a valve stem 36 which is urged upwardly by a spring 38 tending to seat the valve 28 on a knife edge 40 provided by a valve seat member 42. The spring 38 is interposed between a shoulder 44 provided by the valve seat member 42 and a pin 46 extending transversely through and projecting from both sides of the valve stem 36.

2

The fuel valve 28 is moved to open position by a pair of diaphragms 48 and 50 located respectively in diaphragm chambers 52 and 54. The diaphragm chamber 52 is formed between the cupped upper end of the carburetor body 10 and the web 56 of a spacer ring 58, whereas the diaphragm chamber 54 is formed between the web 56 and a cover 60. The spacer ring 58 and cover 60 are secured to the body 10 by screws 62 and 64.

The diaphragm 48 is formed of a specially treated material which is impervious to gas, gasoline, and oil, and which has a certain amount of flexibility permitting the central part of the diaphragm to move in a vertical direction while the periphery of the diaphragm is firmly clamped between the spacer ring 58 and the upper end of the body 10. The central part of the diaphragm 48 is provided with oppositely disposed metal plates 66 and 68 secured to the diaphragm 48 by a rivet 70. The lower face of the rivet 70 rests upon the upper end of valve stem 36 but a spring 72 interposed between plate 66 and shoulder 74 prevents this rivet from exerting any downward force on valve stem 36 as a result of the action of gravity on diaphragms 48 and 50 and push rod 76.

The upper diaphragm 50 may be of the same construction as the lower diaphragm 48. The periphery of diaphragm 50 is firmly clamped between cover 60 and spacer ring 58 and the rivet 78 which clamps metal plates 80 and 82 to the central portion of this diaphragm rests upon the upper end of push rod 76. The upper sides of the diaphragms are in open communication with each other and with atmosphere by way of passages 84, 86, 88, 90, 92, and 94, the latter three passages being provided in the special screw 64. The upper diaphragm 50 is a dry diaphragm and its lower side is in communication with venturi 18 by way of passages 96, 98, and 100. The lower diaphragm 48 is a wet diaphragm and has its lower side in communication with the fuel passages in a manner which I shall hereinafter describe.

The fuel valve 28 controls flow of fuel from the chamber 26 to a second chamber 102 formed in the valve member 42. This second chamber communicates with the main jet 30 by means of passages 104, 106, 108, and valve chamber 110. A needle valve 112 may be adjusted to regulate the amount of fuel delivered by the jet 30 and this needle valve is held in adjusted position by a spring 114. The valve chamber 110 and valve structure therein is shown more clearly in Fig. 2.

The valve chamber 110 is formed in a two-diameter hollow plug 112 which is threaded into the body 10 and has its lower end closed except for the jet 30 by a disc 114 press fitted and driven into the plug 112. This plug provides an annular valve seat 116 adapted to be engaged by a valve member 118 when the latter is raised by reverse flow, that is, flow of air into the jet 30. The valve member 118 is a free disc of thin material such as metal or cloth and normally rests on the raised ends of a support 120 so that fuel may flow freely down passage 108 and around valve member 118 to jet 30.

Fuel chamber 102 also communicates with idle jet 32 and orifice 34 to supply fuel thereto. This communication is by way of passage 124, valve chamber 126, and passages 128, 130, and 132. The upper end of passage 124 communicates with diaphragm chamber 52 beneath diaphragm 48.

A feature of my invention lies in the particular means for admitting additional air when the engine is operating at high speed full throttle, thus giving the effect of an expandable carburetor. The lower part of the carburetor body 10 is formed to provide an elongated valve chamber 134 closed by a cover 136 secured to the main body 10 by screws 138 and having a suitable sealing gasket 140. A port 142 connects one end of elongated chamber 134 with the choke bore 14 and a second port 144 connects the other end of the valve chamber 134 with the throttle bore 20. Within the chamber 134 is a reed valve 146 secured at one end to body 10 by screw 148.

The valve 146 may be made of thin sheet steel or other suitable resilient material and normally lies in the full line position shown in Fig. 1. In this position it closes the port 142 to prevent flow of air through this port and into chamber 134. However, when the differences in pressure between the choke bore 14 and throttle bore 20 become sufficiently great, the suction in chamber 134 causes the free end of the valve 146 to flex downwardly as indicated in dotted lines to admit additional air to the engine.

It will be understood of course that the carburetor is intended to be attached to the intake port or manifold of an engine in any suitable manner and that fuel inlet 24 is to be connected to a suitable source of fuel supply. If desired, an air filter may be attached to the inlet end of the carburetor. Preferably, the source of fuel supply is either a fuel pump or a tank located slightly above the carburetor and feeding thereto by gravity.

In operating my novel carburetor, needle valves 112 and 126 are opened from one-half to three-fourths of a turn, and if the engine is cold, the choke valve 16 is closed or partly closed to enrich the starting mixture; the throttle valve 22 would be partly opened; the engine is cranked and produces a flow of air through the carburetor. Suction caused by this flow of air through venturi 18 is conducted by means of passages 100, 98, and 96 to the lower side of diaphragm 50, with the result that this diaphragm is moved downwardly by the atmospheric pressure thereabove and opens fuel valve 28. Thereupon fuel flows past this valve and through the short passages communicating with the jets 30 and 32 and orifice 34. This opening movement of the fuel valve 28 is also aided by diaphragm 48 since the lower side of this diaphragm communicates with high speed jet 30 by way of passages 124, 126, 104, 106, 108, and valve chamber 110. If the choke valve is closed or partly closed

during the starting operation, this valve is returned to fully open position as soon as the engine warms up. The throttle valve 22 of course is adjusted to give the desired speed of engine operation under the load imposed thereon.

It will be noted that the upper sides of both diaphragms 48 and 50 are at all times exposed to atmospheric pressure. The lower side of the upper or dry diaphragm 50 communicates with the venturi 18 so that the pressure beneath this diaphragm reflects the suction created in the venturi 18 by the flow of air therethrough and thus varies with engine demand. The lower diaphragm acts as a pressure regulator since the space therebeneath is filled with fuel. This diaphragm tends to vary in accordance with fuel pressure and gives automatic compensation for variations in the fuel pressure at the fuel intake of the carburetor.

20 The size of the ports 142 and 144 and the spring tension of the reed valve 146 are such that this valve remains closed during the starting operation and even when the engine is operating at lowest speed with wide open throttle valve. 25 However, if the engine speed at wide open throttle is increased, as, for example, by decreasing engine load, the reed valve 146 flexes downwardly to permit additional air to bypass venturi 18 by flowing through port 142, chamber 134, and port 144 to the throttle bore. This opening of 30 the reed valve is produced by the increased suction at the higher engine speeds and the suction deflects the free end of the reed valve away from port 142. This arrangement produces in 35 effect an expandable carburetor since it gives in the wide open range an air valve carburetor, without, however, giving the extreme sensitivity of mixture quality produced by an air valve carburetor at the idling and other low speed part 40 throttle running conditions.

From the foregoing description of the construction and mode of operation of my carburetor, it will be seen that I have provided a novel carburetor having one wet diaphragm and one dry diaphragm both cooperating to control the fuel valve. This arrangement is advantageous in providing more opening force and permits the use of a stiffer valve spring to provide a more positive valve-closing action. Furthermore, the 45 two diaphragms in effect separate two functions while combining the effects of these two functions to afford a more accurate control of the fuel valve. One of these functions is compensation for variation in fuel pressure at the carburetor inlet due to variations in pump pressure or 50 variations in fuel level in a gravity system. The other function is compensation for variations in engine demand. In this connection I wish to point out that the dry diaphragm connects with the point of highest suction and flexes more rapidly than the wet diaphragm to respond to engine acceleration and other variable conditions 55 of engine operation.

I also wish to call attention to the simplicity 60 of the fuel valve control and the fact that the frusto-conical valve and its seat are the only parts requiring precision manufacture. The pin 16 may form a relatively sloppy fit in the web 56 and the other parts of the fuel control assembly 65 may be readily made on conventional high production equipment within tolerances suitable for such equipment.

Another feature of my invention lies in the 70 arrangement of the parts whereby the fuel valve 75 is located close to the jets 30 and 32 and orifice

34 so that variations in the effect of gravity on the operation of the carburetor when the latter is inverted is held to a minimum. Also, the passages connecting the fuel inlet with the delivery points are short and without unnecessary restrictions so that the fuel may flow freely therethrough except to the extent that it is controlled by the needle valves.

Another feature of my invention lies in the provision of the check valve 118 and its associated structure. This check valve is located in the fuel supply line to the main jet 30 but in no wise interferes with flow of fuel to that jet. On the other hand, this check valve closes instantly upon the creation of a condition which would tend to cause back-bleed through the high speed jet and thereby insures accurate metering of the fuel and smooth operation when the throttle valve is in idle position or only slightly opened.

In Fig. 3, I have shown an assembly utilizing a simplified and less expensive form of my novel carburetor. In this figure I have shown a carburetor having a body 150 provided with a choke bore 152 having the usual choke valve 154 mounted therein. The carburetor also has a throttle bore 156 provided with a conventional throttle valve 158. Between the two bores is a simplified restriction 160 in the form of a plate 162 having a central orifice. The plate 162 may be press fitted or otherwise secured in the body of the carburetor.

Communicating with the throttle bore are three orifices 164, 166, and 168, all of which connect with the passageway 170. Leading into the passageway 170 is an orifice 172 forming a valve seat for a needle valve or other adjustment valve 174. A valve chamber 176 connects the orifice 172 with passage 178 and threaded inlet 180 adapted to receive the fitting 182 of a fuel line 184 which extends downwardly and into the fuel supply reservoir 186. This reservoir is preferably shallow and located immediately beneath the carburetor to minimize the fuel lift and variations in fuel head in the reservoir. The reservoir may be vented as indicated at 188.

An elongated valve chamber 190 is parallel with the main axis of the carburetor and has openings or ports 192 and 194 connecting this valve chamber with the choke and throttle bores respectively. Attached to the carburetor body by means of a screw 196 is a reed valve 198 so arranged that it normally lies flat as shown and covers or seals the port 192 to prevent flow of air from the choke bore through the reed valve chamber and thus into the throttle bore.

If desired, means may be provided for adjusting the spring tension of the reed valve 198. Such adjusting means may assume various forms but in the particular embodiment shown this means is illustrated as composed of an adjusting screw 200 threaded into the cover 202 and serving to vary the compression of a coil spring 204 interposed between the screw 200 and the free end of the reed valve 198. In this arrangement the screw 200 is a high speed adjustment effecting the richness of the engine mixture at high speeds only, whereas the needle valve 174 constitutes the low speed adjustment.

The carburetor shown in Fig. 3 is an extremely simple form of carburetor of a type suitable for use on the less expensive types of engine-driven lawn mowers. In such installations the supply tank is made relatively shallow so that the mixture variation between a full and nearly empty tank does not unduly affect the operation of the

carburetor. Also, this tank is located immediately beneath the carburetor so that the overall fuel lift is maintained at a minimum.

In the better grade of lawn mowers and other small engine installations, the fuel tank is located above the carburetor and fuel runs by gravity from the fuel tank down into the carburetor. In utilizing this form of my carburetor in such an installation, a float mechanism would be interposed between the fuel supply line and the carburetor proper.

While I have illustrated only two forms of my invention, it is to be understood that my invention is not limited to the particular embodiments shown but may assume numerous other forms and includes all modifications, variations, and equivalents coming within the scope of the appended claims.

I claim:

1. In a carburetor, a casing having a choke bore and a throttle bore in axial alignment with the diameter of the choke bore being at least substantially equal to that of the throttle bore, a restriction between said bores, said choke bore being adapted to communicate on its inlet side with a source of air, and said throttle bore being adapted to communicate on its outlet side with the intake manifold of an internal combustion engine, a throttle valve in the throttle bore, a bypass passage around said restriction communicating at its ends with said choke and throttle bores, respectively, adjacent to the restriction, valve means biased to normally close said passage, said valve means being responsive to a pressure differential between said two bores corresponding substantially to full open throttle and less than normal engine load for said throttle opening, for opening said passage to bypass air around said restriction and thereby provide greater air flow between said two bores, and means for supplying fuel to air passing through said bores.

2. A carburetor as set forth in claim 1 in which the choke bore and throttle bore are substantially straight and in which the bypass passage is formed in the casing immediately adjacent to and parallel to said bores.

3. A carburetor as set forth in claim 1 in which said valve means is adjustable to thereby vary the pressure differential required to operate said valve.

4. A carburetor as set forth in claim 1 in which said two bores are substantially straight and in which said bypass passage is formed in said casing immediately adjacent to and parallel to said bores, said valve means comprising a reed valve secured to said casing within said bypass passage, and a removable cover forming a wall of said passage and providing access to said reed valve.
